CLAIM

The ornamental design for a stock pot, as shown and described.

DESCRIPTION

The patent or application contains at least one drawing executed in color photograph. Copies of this patent or patent application publication with color photograph(s) will be provided by the Office upon request and payment of the necessary fee.

FIG. 1 is a perspective view of a first embodiment of a stock pot in accordance with the subject disclosure.

FIG. 2 is a right side view of the first embodiment of the stock pot seen in FIG. 1.

FIG. 3 is a left side view of the first embodiment of the stock pot seen in FIG. 1.

FIG. 4 is a front view of the first embodiment of the stock pot seen in FIG. 1.

FIG. 5 is a back view of the first embodiment of the stock pot seen in FIG. 1.

FIG. 6 is a top view of the first embodiment of the stock pot seen in FIG. 1; and,

FIG. 7 is a bottom view of the first embodiment of the stock pot seen in FIG. 1.
